FORK OR SIMILAR ARTICLE OF FLATWARE

Siro R. Toffolon, Meriden, Conn., assignor to The International Silver Company, Meriden, Conn., a corporation of Connecticut

Filed Dec. 18, 1967, Ser. No. 9,814

Term of patent 14 years

U.S. Cl. D54—12
Int. Cl. D7—03

FIG.1.

FIG.2.

FIG.3.

FIG.4.

FIG.5.

FIG. 1 is a front elevational view of a fork showing my new design;

FIG. 2 is a rear elevational view;

FIG. 3 is a side elevational view;

FIG. 4 is a cross-sectional view taken on line 4—4 of FIG. 1; and

FIG. 5 is a cross-sectional view taken on line 5—5 of FIG. 1.

The essential features of my design for a fork or similar article of flatware reside in the configuration of the handle in combination with the particular pattern of surface ornamentation applied thereto.

The design is intended for use on sets comprising forks, spoons, knives and similar articles of flatware.

I claim:

The ornamental design for a fork or similar article of flatware, substantially as shown and described.
